(57) **CLAIM**

The ornamental design for a smart phone attachment, as shown and described.

DESCRIPTION

FIG. 1 is a top, front, left side view of a smart phone attachment design, according to the present invention; FIG. 2 is a bottom, front, right side view of the design of FIG. 1;

FIG. 3 is a top, rear, left side view of the design of FIG. 1; FIG. 4 is a top, rear, right side view of the design of FIG. 1; FIG. 5 is a top view of the design of FIG. 1;

FIG. 6 is a bottom view of the design of FIG. 1; FIG. 7 is a left side view of the design of FIG. 1; FIG. 8 is a right side view of the design of FIG. 1; FIG. 9 is a front view of the design of FIG. 1;

FIG. 10 is a rear view of the design of FIG. 1; and, FIG. 11 is a top, front, right side view of the design of FIG. 1, with the smart phone attachment in a folded configuration. The broken lines delineate an area not included in the scope of the claimed invention, and form no part thereof.

1 Claim, 6 Drawing Sheets
